United States Patent Office

Des. 175,311
Patented Aug. 9, 1955

175,311

CAN OPENER

George A. Lehmann, Ferguson, Mo., assignor to The Dazey Corporation, St. Louis, Mo., a corporation of Missouri

Application April 29, 1955, Serial No. 35,751

Term of patent 14 years

(Cl. D22—2)

FIG. 3.

FIG. 1.

FIG. 2.

Fig. 1 is a top plan view of a can opener, embodying my new design;

Fig. 2 is an elevational view showing one side of the can opener, and

Fig. 3 is an elevational view of the opposite side of the can opener.

I claim:

The ornamental design for a can opener, substantially as shown.
